(57) **CLAIM**

The ornamental design for a mask with LED lighting, as shown and described.

DESCRIPTION

FIG. 1 is a front, perspective view of a mask with LED lighting, showing my new design, in a used condition shown on a human figure in broken lines;

FIG. 2 is a front view thereof;

FIG. 3 is a rear view thereof;

FIG. 4 is a top view thereof;

FIG. 5 is a left side view thereof;

FIG. 6 is a right side view thereof;

FIG. 7 is an exploded view thereof; and,

FIG. 8 is another exploded view thereof.

The broken lines shown in the drawings form no part of the claimed design.
